WINDING MACHINE

Everett H. Cobb, Pawtucket, R. I., assignor of
one-half to Roscoe N. Stokes, Barrington, R. I.

Application December 12, 1942, Serial No. 468,747

8 Claims. (Cl. 242—43.7)

This invention relates to a winding machine and more particularly to a filling winder.

One of the objects of this invention provides mechanical means for controlling the amount of yarn that will be utilized for the bunch that is placed upon each of the bobbins so that excess may be avoided.

Another object of the invention is to lay the yarn bunch on the bobbin with a traverse motion that it may be distributed evenly along the package forming a flat tight winding on the bobbin.

Another object of this invention is to provide mechanical means for building a bunch which will become automatically disconnected from control of the yarn to permit the main traverse motion of the machine to control the yarn after the bunch has been formed.

Another object of this invention is to provide simple addition to a machine now already in existence by which this automatic bunch building mechanism may be attached to existing machines.

Another object of this invention is to provide a simple control which may be produced inexpensively and will in a short time pay for itself in a saving of time of the operator.

With these and other objects in view, the invention consists of certain novel features of construction, as will be more fully described and particularly pointed out in the appended claims.

In the accompanying drawing:

Fig. 1 is an end elevation illustrating a winding machine equipped with my invention;

Fig. 2 is a fragmental view looking at the machine from right angles to that shown in Fig. 1 illustrating the ratchet feed of the screw shaft of the building mechanism;

Fig. 3 is a fragmental view at substantially line 3—3 of Fig. 1;

Fig. 4 is a view on substantially line 4—4 of Fig. 3; and

Fig. 5 is a section substantially on the line 5—5 of Fig. 3 showing the carrier for the follower roll.

In proceeding with this invention I provide an attachment for a winding machine which will obtain control of motion transmitted to the rocking member through which the traversing of the yarn is controlled and then disconnect this mechanism to permit the usual main traverse to continue with its operation after a predetermined length of time for the building of a bunch. An arrangement for adjustment of the length of time which the auxiliary mechanism exerts its control is provided and I utilize the mechanism which previously advanced the traverse step by step along

the bobbin for feeding the auxiliary mechanism to move it out of control of the yarn at the desired time.

With reference to the drawing 10 designates the frame at the end of the machine where the builder motion is located. Yarn designated 11 is lead from a suitable supply to the bobbin 12 and is so vertically traversed as to cause a package which has a taper at either end, as indicated in dotted line at 13, to be built. There are a plurality of yarn ends typified by the single end 11 shown and each of these lead to a separate bobbin. Each yarn end extends beneath a long bar 14 and over a similar bar 15 which bars are carried by swinging arms 16 which rock up and down to traverse the yarn along the bobbin. Arms 16 are mounted on a shaft 17 which rocks in bearings provided by brackets 18 supported from the frame work of the machine as at 19 and 20. A lever 21 extends outwardly from the shaft 17 and is keyed thereto and this lever is connected to a rod 22 upon which a downward pull is exerted by the builder mechanism while a spring 23 acting upon a segmental arm 24 tends to swing the lever 21, arm 16, and traversing bars upwardly. The bell crank lever 25 pivoted on the frame of the machine as at 26 provides one arm 27 to which the link rod 22 is secured as at 28 in the slot 29. The pull of the spring 23 tends to swing the arm 30 of the bell crank lever 25 toward the right as shown in Fig. 1 so that its enlarged face 31 will be normally in engagement with the threaded end 32 of the rod 33.

Swinging arm 34 is pivoted at 35 on the frame 35 10 of the machine and carries a nut 36 pivotally mounted as at 37 at the upper end of this arm which nut has threaded engagement with the threaded portion of the rod 33. The other end of this rod extends loosely through a bearing 38 positioned at the upper right side of the frame 10 and rockably carries bracket 39 (see Fig. 2) which has a pawl 40 pivotally mounted thereon. This pawl 40 engages a ratchet 41 slidably mounted on shaft 33 and keyed thereto to rotate therewith. Thus, as the arm 34 rocks, the shaft 33 carried thereby will slide through the ratchet 41. The bracket 39 is engaged by a cam 44 mounted on shaft 45 and driven by gear 46 which in turn is driven by the train of gears 47, 48 and belt driven wheel 49. Thus an intermittent rotary motion is imparted to shaft 33 in a usual and well known manner.

A heart shape cam 50 is also mounted upon shaft 45 which is engaged by cam follower 51 carried by arm 52 pivoted as at 53 to the frame-

work of the machine while on the opposite edge surface 53 of this arm 52 a roller 54 is provided to engage the same and transfer rocking motion of the arm 52 to the arm 34. The roller 54 is mounted in a carriage designated generally 55 carried by the arm 34 but slideable therewith (see Fig. 5).

The carriage 55 has a dove-tail connection with the arm 34 so as to slide therewith and is provided with a rack 56 extending upwardly therefrom (see Fig. 3) the teeth 57 of which engage a pinion 58 mounted upon shaft 33 so as to rotate and move axially therewith. As the shaft 33 is rotated, by the pawl and ratchet arrangement above described, it will be moved axially in the nut 36 and move the pinion 58 therewith and out of engagement with the rack teeth 57. The timing however being such that the carriage 55 will have been moved to its lowermost position prior to the complete disengagement of pinion 58 and rack teeth 57. The mechanism so far described forms part of the builder motion of the Johnson and Bassett Inc. winders.

My attachment consists of an arm 60 slotted as at 61 and attached to the member 25 by means of a bolt 62 extending through the slot and into the arm 30 of the rockable member. This bar 60 is supported in a frame 63 which is adjustably attached by bolt 64 to a bracket 65 which I drop from the carriage 55 attaching the same thereto as at 66. This bracket is slotted as at 67 so as to provide for adjustment of the frame or box-like structure 63 which supports the bar 60 but permits the same to slide therethrough freely.

An additional cam 67 is provided on the shaft 45 held in place by a nut and which will be located in the same plane as the bar 60. A connecting link consisting of an arm 68 which is pivoted as at 69 to the frame is located between and in the same plane as the cam 67 and the bar 60 and is engaged by both the cam and the end of the bar so as to transmit motion from the cam to the bar. When the cam 67, arm 68, and bar 60 are in engagement the distance between the center of the shaft 45 and the rock member 25 will be such that the broad face 31 of the arm 30 will be out of engagement with the end 32 of the rod 33 and the oscillation of the arm 34 will have no effect on crank lever 25. The crank lever 25 in this situation will be oscillated by the motion derived from cam 67 through the connection 60 and 68 as previously described. In turn this motion will be transmitted to the arms 16 and bars 14-15 secured thereto to initially traverse the yarn at the lower end of the bobbin and form a winding or bunch of yarn thereon of a length and distribution governed by the predetermined throw and shape of the cam 67 and distance of movement imparted to the bar 60 along the arm 68.

In the present instance during this initial rocking of the crank lever 25 the arm 34 will be oscillating from the motion derived from the cam 50 in timed relation and in the same direction as crank lever 25 so as to maintain the separation of the end 32 of shaft 33 and enlargement 31 of lever 25. Also, during the oscillation of arm 34 the shaft 33 and pinion 58 will be intermittently rotated and moved axially. This rotation of pinion 58 will through its connection, now had with the rack 56, lower the carriage 55 and bracket 65 fixed thereto to move the end extremity of the bar 60 progressively along the arm 68 towards its lower end and thereby increase the distance between the fulcrum of the arm 68 and the point

of contact of the bar 60 therewith. This will increase the arc of rocking of lever 25 and in turn increase the length of traverse of the bars 14-15 during the forming of the bunch. However, the arm 68 is of a predetermined length so that when the point 70 of the link 60 which engages the connection 68 moves below the end 71 of this connecting arm then as the link 60 is free to slide and will extend beneath the end 71 of the arm 68 and become disengaged with the arm 68 and the rock member 25 will under the influence of spring 23 move into engagement with the end 32 and be now rocked by the rod 33 and continue with the main traverse of the building motion governed by cam 50 for the formation of the package. There will be an increasing arc of oscillation of the arm 34 because of the increasing distance of the position of the roller 54 on the arm 52 from the fulcrum thereof as the carriage is lowered. This increase will continue until the pinion 58 is axially moved out of engagement with the rack 56. The length of the traverse stroke will then remain constant but there will still be an upward shifting of the path of the bars 14-15 as the angular distance between the arm 34 and crank lever 25 decreases as the shaft 33 is moved axially in the nut 36. At the start of each set of packages it will be necessary to raise the carriage 55 to a predetermined height to start the operation of the bunch building machine and to axially extend the end of the shaft beyond the arm 34 to the initial setting of the builder mechanism.

Prior to setting the machine in motion to package a new doff of bobbins the rod 33 is rotated by means of a handle (not shown) to advance the rod through the nut 36 towards the left side of the machine as viewed in Fig. 1.

The rotation of the rod 33 in a direction to preset the same will also rotate the pinion splined thereto in a direction to raise the carriage 55 and set the same at its upper initial position. In this upper position of the carriage, the bar 60 carried thereby will have been positioned to have the end thereof engage with the depending arm 68. In this situation the arm 30 of the crank lever 25 will be held out of contact with the end 32 of the rod 33. This condition will be maintained so long as the bar 60 is held in contact with the arm 68. The spring 23 through proper connecting elements will exert sufficient force to cause the end of the bar to move into engagement with the arm 71 and follow the swinging motion thereof.

Now with the yarn in proper position on the guides and with the free end of the yarn wrapped a few turns about the butt end of the bobbin, the machine may be set into motion.

The rotation of the cam 67 will impart a swinging motion to the arm 68 which in turn will be imparted to the crank 25 through the bar 60. This action will provide a short or bunch building traverse to the yarn guides.

During the rotation of the cam 67 a similar rotation of the cam 44 takes place which at every turn actuates the pawl arm 39 to advance the ratchet 41 a predetermined portion of a revolution. This action rotates the rod 33 a similar portion of a revolution in the nut 36, which shortens the distance the rod extends to the left of the nut 36. The action also provides for a partial rotation of the pinion 58 in a direction to lower the carriage 65 and the bar 60 carried thereby. Eventually the bar 60 will be carried below and out of engagement with the depend-

ing arm 68. It may be here pointed out that since the distance between the pivotal connection of the arm 68 and the point of engagement with the bar 60 increases there will be a proportional increase in the arc of swing of the crank 25 which will provide an increase in the traverse of the yarn guides.

The disengaging of the bar 60 with the arm 68 will permit through the pull of the spring 23, the engagement of the builder screw 33 with the shoe 31 on the arm 30. Now the further traverse of the yarn guides will be through the action of the main cam 50, arm 52, arm 34, rod 33, and crank 25. It is here noted that the threaded rod 33 is carried by the arm 34 to and fro in a slight arc since the nut is carried by the arm 34. This line of path of the rod 33 is permitted because of a loose fit of the rod in the bearings and pivoting the nut 37 to the arm 34.

The mechanism which I have provided is simple and utilizes controls already on the machine. The attachment may be made quickly and inexpensively to machines already in existence and the operator is thus free during the time usually spent at the start of each operation for other work while the other advantages in saving of yarn and less experience for operation will be readily apparent.

I claim:

1. In a filling winder, a thread guide, a rockable member through which traversing of the thread guide is controlled, mechanism engageable by said rockable member to rock the same, auxiliary mechanism including a bar engaging said rockable member and operatively connected to the first said mechanism, a cam and an intermediate part engaged by the bar and cam to transmit motion from the cam to the said rockable member and to hold the rockable member out of contact with the said first mechanism, and means in said first mechanism also serving to control the engagement of said bar and intermediate part for a predetermined period followed by release of control of the auxiliary mechanism to the control by the said first mechanism.

2. In a filling winder, a thread guide, a rockable member through which traversing of the thread guide is controlled, mechanism engageable by said rockable member to rock the same, auxiliary mechanism including a bar operably connected to the first said mechanism, means for adjustably connecting said bar to said rockable member, a cam, an intermediate part engaged by said cam and said bar to transmit motion from the cam to said rockable member and hold said rockable member out of contact with the first said mechanism, said first mechanism also serving to control the engagement of said bar and intermediate part for a predetermined period followed by release of control of the auxiliary mechanism to the control by the first said mechanism.

3. In a filling winder a thread guide, a rockable member through which traversing of the thread guide is controlled, mechanism engageable by said rockable member to rock the same, including means normally operable to increase the arc of rocking motion of said rockable member as winding proceeds, auxiliary mechanism including a bar engaging said rockable member, a cam, an intermediate part engaged by said bar and said cam to transmit motion from the cam to the bar to rock said rockable member and hold the same out of contact with the first said mechanism, said bar being supported into en-

gagement with said intermediate member by the said means operable to increase the arc of rocking of said intermediate part and to move it out of engagement with said intermediate part after a predetermined operation of said means operable to increase the arc of rocking motion of said rockable member.

4. In a filling winder, a thread guide, a rockable member through which traversing of the thread guide is controlled, mechanism engageable with said member to rock the same including means normally operable to increase the arc of rocking motion of said rockable member as winding proceeds, auxiliary mechanism including a bar engaging said rockable member, a cam, an intermediate part engaged by said bar and said cam to transmit motion from the cam to the bar, and hold the same out of contact with the first said mechanism, said means being adjustably supported on the said means operable to increase the arc of rocking of said rockable member to position said bar to engage said intermediate part and to move it out of engagement therewith after a predetermined operation of said advancing means, said adjustment serving to vary the predetermined timed relation of the auxiliary operation.

5. In a winder, a thread guide, a rockable member through which motion is transmitted to said thread guide, a mechanism for rocking said member including an arm mounted for oscillatory movement, means carried thereby engageable by said rockable member, a carriage movable on said arm, a bar secured to said rockable member and to said carriage, said bar being movable with said carriage and relative thereto, a cam, an intermediate part engaged by said cam and said bar to hold said rockable member out of contact with the said means carried by the said arm so as to transmit motion from said cam through said bar to initially rock said rockable member at the beginning of the winding, and means for moving said carriage during said initial rocking of said member to disengage said bar from said intermediate member after a predetermined period of initial rocking of said rockable member to permit engagement of the said means carried by the said arm with the rockable member.

6. In a traverse mechanism, a rockable member, an arm mounted for oscillatory movement, means carried thereby engageable by said rockable member for rocking the same, a carriage movably mounted on said arm, a bar secured to said rockable member and to said carriage, said bar being movable with said carriage and relative thereto, a cam, an intermediate part movably mounted and engageable by said bar and cam for transmitting motion from said cam to said rockable member through said bar, and means for moving said carriage for disengaging said intermediate part and said bar after a predetermined period of rocking of said member through said bar.

7. In a filling winder, a thread guide movable in a generally vertical direction, a rockable member through which motion is transmitted to said thread guide, mechanism engageable with said rockable member normally operable to rock the same, auxiliary mechanism including a bar engaging said rockable member and operatively connected to the first said mechanism, a cam, an intermediate part engaged by said bar and cam to hold said rockable member out of contact with the said first mechanism to transmit motion from

said cam to said bar to initially rock said rockable member for a predetermined period at the beginning of the winding, means including the said first mechanism for disengaging said auxiliary mechanism from said member, and means for causing engagement of said rockable member and first said mechanism.

8. In a filling winder, a thread guide movable in a generally vertical direction, a rockable member through which motion is transmitted to said thread guide, mechanism engageable with said rockable member to rock the same, resilient means tending to move said member into engagement with said mechanism, auxiliary mechanism

including a bar carried by said rockable member and operatively connected to the first said mechanism, a cam, an intermediate part engaged by said bar and cam to hold said rockable member out of contact with the first said mechanism and transmit motion from said cam to said rockable member to initially rock the same for a predetermined period at the beginning of the winding and means including the said first mechanism for disengaging said bar and said intermediate part to permit said resilient means to move said rockable member into engagement with the said first mechanism.

EVERETT H. COBB.
